No. 758,242.

PATENTED APR. 26, 1904.

W. H. GOLDING.

PLATE HOLDER AND ADJUSTER.

APPLICATION FILED FEB. 16, 1903.

UNITED STATES PATENT OFFICE.

WILLIAM H. GOLDING, OF BOSTON, MASSACHUSETTS.

PLATE HOLDER AND ADJUSTER.

SPECIFICATION forming part of Letters Patent No. 758,242, dated April 26, 1904.

Application filed February 16, 1903. Serial No. 143,556. (No model.)

To all whom it may concern:

Be it known that I, WILLIAM H. GOLDING, a citizen of the United States, residing at Boston, in the county of Suffolk, State of Massachusetts, have invented certain new and useful Improvements in Plate Holders and Adjusters, of which the following is a specification, reference being had therein to the accompanying drawings.

10 This invention relates to a plate holder and adjuster particularly adapted for securing electrotype-plates to the grooved iron base-block usually used therewith and adjusting said plates for multicolor work.

15 The invention has for an object to provide an improved construction of register-gage for the purpose of securing an accurate adjustment of successively-used plates in multicolor work, so that the margin thereof will be exactly alike and a perfect register secured for each color.

20 A further object of the invention is to provide an improved form of wedge-clamp cooperating with these gages to secure the plate in fixed position when the desired adjustment is reached.

25 Other and further objects and advantages of the invention will be hereinafter set forth and the novel features thereof defined by the 30 appended claims.

In the drawings, Figure 1 is a plan showing the register-gages and wedge-clamps applied to a plate, the base upon which said plate is disposed being broken away. Fig. 2 is a detail vertical section on the line 2 2 of Fig. 1; Fig. 3, a detail perspective with the parts of the register-gage separated; Fig. 4, a vertical section through one of the wedge-clamps on the line 4 4 of Fig. 1; Fig. 5, a detail perspective of said clamp with the parts separated; Fig. 6, an elevation of the fork-wrench for operating both the register-gage and wedge-clamp, and Fig. 7 a section showing a modified application of the clamping-block.

35 Like letters of reference refer to like parts. The letter A designates a metallic base, preferably that ordinarily used, which is provided with a series of undercut channels or ways A' of any form—for instance, having

inwardly beveled or inclined side walls A², as shown in Fig. 3—while the plate B, containing the matter to be printed, is disposed upon this base and the edges thereof preferably beveled, as at B', to secure the most desirable contact with the holding devices. The register-gage is composed of a screw member C, adapted to thread into a divided clamping-block C', having oppositely-beveled walls C², which when the screw is tightened contact with the walls A² of the base A and also with the threads of the screw to thus firmly hold the gage in position. The head C³ of this screw is provided with a transverse slot C⁴ for the application of a tool for clamping the parts together and also with a socket C⁵ for a purpose hereinafter described. The periphery of the head C³ has an inclined wall B⁵, adapted to bear against a similarly-inclined wall C⁶, formed in the cam-ring C⁷, while the outer periphery of this ring is also beveled, as at C⁸, to fit within a beveled inner periphery C⁹ of the contact-plate C¹⁰, which is provided with a beveled edge C¹¹ to bear against the edge B' of the plate B. The clamping-block C', screw C, and contact-plate C¹⁰ may be used without the other parts 75 of the gage, as shown in Fig. 7. This contact-plate is preferably of rectangular formation, so as to secure an extended bearing-surface upon the edge of the printing-plate, while the cam-ring C⁷ is provided with a 80 socket C¹² therein, adapted to receive an adjusting-tool of any desired character—for instance, an ordinary fork-wrench, such as illustrated in Fig. 6, one prong D' of which enters the socket and the other separated 85 prong or projection D' of which fits in the central socket C⁵ of the screw, thus permitting an adjustment of these parts as the wrench is turned, the socket C⁵ acting as a pivotal point. In many cases this adjustment is very delicate 90 and for a degree not thicker than a printing-line. In order to secure the greatest accuracy, it has therefore been found important to provide the contact-plate C¹⁰ and the cam-ring C⁷ with graduations or indicating-marks 95 D², which may be set in alinement with each other when the gage is adjusted into contact with the first plate used, so that any move-

ment in the adjustment of a subsequent plate will be indicated by the difference in alinement between the graduations upon the gage.

The register-gages just described are disposed upon one side and one end of the plate, while upon the opposite side and end the wedge-clamps E are disposed. These are composed of two parts E' and E², each having a beveled face E³ to contact with the inclined walls A² of the slot A', within which they are disposed, while the member E' is provided upon its upper surface with an angular contact-plate E⁴, having a beveled edge E⁵ to bear against a similar edge B' of the plate B, and a wrench-socket E⁶, disposed midway of the length thereof. The member E' is provided with a head E⁷, adapted to rest upon the upper surface of the base A, and with a transverse slot E⁸ adapted to receive one prong of the fork-wrench D. The inner face E⁹ of the member E² is inclined longitudinally, while the member E' is provided with a similar inclined face E¹⁰, so as to secure a lateral wedging of the parts as they are drawn together, this incline being disposed in opposite directions for the side and head clamps, as will be seen in Fig. 1. The clamp is adjusted by introducing a prong D' of the fork-wrench into the socket E⁶ of one member and the other prong into the slot E⁸ of the opposite member, thus moving the members longitudinally to each other, producing the wedging action just described. These members may be graduated similar to the register-gage to determine the extent of their movement.

In the operation of the invention the plate to be printed from is secured upon the base in proper position by means of the register-gages and wedge-clamps and the desired impressions made therefrom. In multicolor work this plate is then removed and another plate introduced in its place. This removal is effected by loosening the clamp-wedges to release the first plate, and the plate for the second color is then placed in the same position in contact with the register-gages, which are still secured at their initial adjustment. Owing to the fact that the plates are seldom exactly alike and that it is frequently desired to produce the second-color impression in exact alinement with the first or in a positive relation thereto it becomes necessary to effect a fine adjustment of the plate to secure a perfect register for each color. This is done without releasing the initial adjustment of these register-gages; but by introducing the fork-wrench into the socket of the screw and cam-ring the latter is rotated upon the screw, the wedge-clamps being still free to move in their slot, and the plate thus adjusted laterally or longitudinally upon the base to the extent desired, this being indicated by the graduations carried by the gage. A proof impression will

immediately indicate the extent of movement necessary for the plate to secure perfect register, and the operator can then by reference to his graduations secure this exact adjustment, thus avoiding the necessity of a number of proof impressions to secure the accurate register. When the parts are in proper position, the wedge-clamps are tightened and the plate firmly secured for printing. It will be seen that this gage can be set to any fraction of its full eccentric movement and graduated for a very fine adjustment, while the clamping-plate presents an extended bearing-surface that will not dent the electrotype with which it contacts. The structure of wedge-clamp also permits the same to be introduced into the slot at any point by placing the members separately therein and bringing them longitudinally together, and owing to the simple construction thereof no tightening-screws are necessary, while the wedging action is found more reliable than a screw-clamp, and the parts of both the gage and clamp are adapted to be operated by a single tool, such as the fork-wrench. It will also be seen that by forming the clamps for the side and end of the plate with opposite inclines any pressure against them increases the clamping action in the slot, so that they cannot work loose, which is the frequent objection to screw-clamps. The split or divided clamping-nut in its upward movement contacts with the wall of the channel and also with the threads of the screw, thus effectually clamping the screw against accidental rotation and the loosening of the block and also holding the block firmly in its position in the channel. It will be seen that when these clamp-blocks and wedge-clamps are correctly set in position the plate is held against possible loosening, as the press-cylinder always moves over the plate in one direction, such movement having a tendency to tighten the holding devices, and thus clamp the plate more firmly. The channel or way herein shown is provided with inclined side walls; but these walls may be of any desired configuration and the contact-faces of both the clamping-block and wedge-clamps correspondingly altered to coöperate therewith.

It will be obvious that there may be changes made in the construction and configuration without departing from the spirit of the invention as defined by the appended claims.

Having described my invention and set forth its merits, what I claim, and desire to secure by Letters Patent, is—

1. In a device of the class described, a slotted base, a wedge-clamp comprising separate members having their adjacent faces inclined, an angular head upon one of said members having a plate-engaging flange extended over the base and provided with a wrench-socket,

and a head upon the opposite member extended over the base and provided with a wrench-socket.

2. In a device of the class described, a base provided with a slot therein having inclined walls, a wedge-clamp comprising separate members having beveled outer faces and inclined inner faces adapted to contact with each other, an angular graduated head upon one of said members having a plate-engaging flange extended over the base and having a wrench-socket therein, and a graduated head upon the coöperating member having a transverse slot therein.

15 3. In a device of the class described, a slotted base, a printing-plate supported thereon, a plate-engaging device comprising a base-supported member having a portion projected laterally above said base, a coöperating relatively movable member in contact with the first-mentioned member and having a portion projected laterally above said base, means carried by one of said members for engaging said plate, and means for jointly adjusting and securing said members above the bottom of the slot in said base.

20 4. In a device of the class described, a base-plate provided with diagonally-disposed slots therein, a printing-plate, register-gages secured in said slots to engage one side and end of said plate, and clamps adjustably secured in said

slots to engage the opposite side and end of said plate and comprising separate members having inclined contact-faces the faces upon the end and side clamps being disposed in diagonally opposite directions to a wall of the slot within which it is secured.

25 5. The combination with a slotted base, of a clamping device comprising two members each provided with a laterally-projecting flange and a divided wedge-shaped depending portion adapted to be suspended within the slot of the base by said flanges, and means for adjusting and for locking said members in their adjusted position.

40 6. In a device of the class described, a diagonally-slotted base, a wedge-clamp comprising separate members each having an inclined face extending longitudinally of the slot within the base and adapted to contact with each other, a contact-face carried by each member of the clamp within the slotted base, and a laterally-extended contact-plate carried by one member of the clamp upon the upper surface of said base and having its plate-engaging faces at an angle to each other.

45 In testimony whereof I affix my signature in presence of two witnesses.

WILLIAM H. GOLDING.
